DOUBLE PLANKED HULL CONSTRUCTION

Andrew J. Higgins, New Orleans, La.

Application December 3, 1938, Serial No. 243,863

5 Claims.

(Cl. 9—6)

This invention relates to a double planked boat hull construction and is concerned particularly with means and a method of construction for making a hull of this type water-tight.

5 Double planking is employed for the most part in light high speed hulls which are subjected to excessive vibration and to weaving, due to their inherent lightness.

It is customary to run the inner and outer 10 planks in different directions so as to cross the joints and as the usual thinness of the planking makes it impracticable to caulk the joints between the planks, recourse is had to a canvas interlining which is laid between the inner and outer planking and preferably cemented to either one or both of the plank surfaces by marine glue, asphalt or other suitable water-proof adhesive. Such canvas lamination applied in the ordinary manner merely covers the joint between the inner 15 and bottom plank panels or the joint between the side and bottom plank panels and the keel.

Inasmuch as the side planks are customarily secured in common to the ribs and the bottom planks are secured in common to transverse ribs 20 or supports, the side and bottom planking may be considered as panels which in the act of weaving move as a whole, producing the maximum relative movement particularly at the chine and also at their juncture with the keel. Due 25 to this relative movement the canvas interliner or lamination as ordinarily applied wears along the chine and keel joints and soon goes into slits, creating leaks which are practically impossible to repair.

30 The present invention has for its principal object to provide a double planked hull construction employing the intermediate canvas lamination not merely as a cover for the joints, but extending through the joint between the outer bottom and side planking at the chine, and through both faces of the rabbet joint between the outside planking and the keel. Thus the outer chine joint and the keel joint are caulked by a textile packing compressed between the 35 abutting surfaces of the joints, for the full width of said abutting faces, and which cannot wear through or go into slits, and therefore ensures a permanent water-tight construction.

Another object is to provide in a double 40 planked hull construction of the type described, an interliner between the inner and side planks having a marginal portion which laps the inner bottom plank adjacent the chine joint and an interliner between the inner and outer bottom 45 planking which extends through the joint be-

tween the outer side plank panel and the bottom plank panel and having a marginal portion which laps upon the side plank panel, said interliners being adhesively united to the surfaces which they contact, forming a pocket in which the chine 5 margin of the side plank panel is adhesively seated and said interliners being mutually united and therefore of double thickness throughout the area in which they overlap beneath the chine.

Other objects of the invention will appear as 10 the following description of a preferred and practical embodiment thereof proceeds.

In the drawing which accompanies and forms a part of the following specification, the sole figure is a perspective view, partly in section of 15 a boat hull embodying the principles of the present invention.

Referring in detail to the structure illustrated in this figure, the numeral 1 represents the keel, 2 being the chine logs, 3 and 4 representing respectively the inner and outer side plank panels regarded as a whole, while the numerals 5 and 6 represent respectively the inner and outer bottom plank panels, likewise regarded as a whole, the individual planks in the inner and outer side 20 plank panels being designated respectively by the characters 7 and 8, while the individual planks in the inner and outer bottom plank panels are denoted by the reference characters 9 and 10.

The figure represents the boat hull in which 30 the inner and outer side planks run diagonally in opposite directions so as to cross the joints while the inner bottom planks 9 extend diagonally and the outer bottom planks 10 extend longitudinally of the keel in the interest of structural stiffness as well as to cross the joints between the inner and outer bottom planks. The arrangement of the planking as described is a matter of option insofar as the present invention 35 is concerned.

The keel 1 is provided with inner and outer rabbets 11 and 12 respectively, receiving the adjacent ends or edges of the inner and outer bottom planking. The ends or edges of the inner and outer side planks 7 and 8 abut flat against 40 the adjacent edges of the inner and outer bottom plank panels, the portions of the inner, side and bottom plank panels which lie against the chine logs 2 being secured to said chine logs.

In the construction of the hull a sliver or yarn 45 of caulking or a length of flat wick packing is preferably placed against the overhanging face of the inner rabbet 11 and the ends or edges of the inner planks 9 are screwed against said face of said rabbet putting the caulking or packing 50

under compression. This gives the initial water-tight seal at the keel and is of itself common practice and not per se to be regarded as a dominant feature of the invention.

5 The invention involves the employment between the two layers of planking of the two flexible textile sheet interliners 13 and 14 which will ordinarily be of canvas. Canvas is of course not inherently water-proof, but in its use as an 10 interliner the canvas is especially treated to render it water-proof either by coating the canvas on one or both sides with a suitable water-proof adhesive such as marine glue or asphalt or by 15 coating the inner planking with the adhesive and applying the canvas which will absorb or take up enough of the adhesive to render it water-proof. The canvas is then preferably but not necessarily 20 coated with adhesive on the other side before applying the outer planking. The present invention contemplates the employment of two of the 25 flexible textile sheet interliners, the interliner 13 starting somewhere along the side of the hull, preferably at the top or sheer and being folded around the chine angle 15 terminating in a marginal overlap 16 which is glued or otherwise 30 united to the inner bottom planking. This interliner covers the joint between the inner side and inner bottom plank panels 3 and 5. The 35 other interliner 14 preferably starts at the keel and it will be observed that it lines both faces of the outer rabbet 12 as indicated at 17 and 18 so that when the edge of the first or garboard plank 40 is in place in the rabbet, the interliner 14 lines both faces of the joint between the garboard plank and the keel. Said interliner 14 extends 45 throughout the space between the inner and outer plank panels, folds around the outer edge 20 of the lower edge of the side plank panel 4 and has the marginal overlap 21 which is glued or otherwise 50 united to the lower portions of the side plank panel. It will be observed that of necessity the interliner 14 passes through the joint between the outer side and bottom panels being contacted by the abutting faces of said 55 joint.

It will likewise be observed that the lower portion of the outer side plank panel 4 is seated in a pocket formed between the interliner 13 and the interliner 14, all surfaces of which pocket are adhesively united to the outer side plank panel. It will also be observed that the interliner 14 crosses the marginal overlap 16 of the interliner 13 forming a seal of double thickness beneath the chine, it being understood that the 55 coinciding layers of interliner are adhesively united in a water-tight manner.

Thus a most efficient joint is formed, in which it is practically impossible that leakage can take place through cutting or wearing of the interliner fabric due to weaving and in which a water seal of double efficiency is provided, one phase of which comprises the side interliner 13 which covers the joint between the inner side and bottom plank panels and the other phase of which is provided by the bottom interliner 14 which extends through the joint between the outer side and bottom plank panels, any possible leakage through this seal being further barred by the double thick joint, of relatively large width 70 formed by the mutually contacting areas of both of said interliners. With reference to the keel it will be understood that the primary seal represented by the compressed packing between the inner bottom plank panel and the inner rabbet 75 is reinforced by the seal formed by the exten-

sion of the interliner 14 through both faces of the outer rabbet and in compression between said faces and the adjacent portions of the garboard plank 19.

For the protection of the marginal overlap 21 5 of the interliner 14 which appears on the outer side of the outer plank panel, an annular shoe 22 is provided which conforms to the chine angle throughout the length of the hull, being suitably secured to the outer side and bottom plank panels 10 and having a flange 23 wide enough to conceal and protect the overlap 21.

While I have in the above description defined what I believe to be a preferred and practical embodiment of my invention, it will be understood 15 to those skilled in the art that the specific details of construction and the arrangement of the parts as shown and described are to be regarded as illustrative and not as restricting the scope of the invention as defined in the appended claims. 20

What I claim is:

1. Double planked boat hull construction comprising inner side and bottom plank panels and outer side and bottom plank panels, the respective inner and outer plank panels making abutting joints at the chine, a water-tight flexible sheet interliner between the inner and outer side plank panels, folded about the inner chine angle and having a marginal lap on the inner bottom plank panel so as to cross the joint between said 30 inner side and bottom plank panels, and a water-tight flexible sheet interliner between the inner and outer bottom plank panels extending between the abutting faces of the joint between the outer side and bottom plank panels, folded about the 35 lower edge of the outer side plank panel and having a marginal portion lapping said outer side plank panel.

2. Double planked boat hull construction comprising inner side and bottom plank panels and outer side and bottom plank panels, the respective inner and outer plank panels making abutting joints at the chine, a water-tight flexible sheet interliner between the inner and outer side plank panels, folded about the inner chine angle 45 and having a marginal lap on the inner bottom plank panel so as to cross the joint between the inner side and bottom plank panels, a water-tight flexible sheet interliner between the inner and outer bottom plank panels extending between the 50 abutting faces of the joint between the outer side and bottom plank panels, folded about the lower edge of the outer side plank panel and having a marginal lap on the outer side plank panel, and a protective angular shoe conforming to the 55 outer chine angle having a flange overlying the marginal lap of the last mentioned interliner.

3. Double planked boat hull construction comprising inner side and bottom plank panels and outer side and bottom plank panels, the respective inner and outer plank panels making abutting joints at the chine, a water-tight flexible sheet interliner between the inner and outer side plank panels, folded about the inner chine angle and having a marginal lap on the inner bottom 65 plank panel so as to cross the joint between the inner side and bottom plank panels, a water-tight flexible sheet interliner between the inner and outer bottom plank panels, contacting the first mentioned interliner throughout the area of the 70 said marginal lap of said first mentioned interliner, said second mentioned interliner extending between the abutting faces of the joint between the outer side and bottom plank panels, folded about the lower edge of the outer side plank panel 75

and lapping the outer side plank panel, said interliners being in adhesive contact with the surfaces which they engage, and forming a pocket receiving the lower marginal portion of the outer side plank panel.

4. Double planked boat hull construction comprising inner side and bottom plank panels and outer side and bottom plank panels, the respective inner and outer plank panels making abutting joints at the chine, a keel having stepped inner and outer rabbets, receiving respectively, the keel edges of the inner and outer bottom plank panels, a water-tight flexible sheet interliner between the inner and outer side plank panels, folded about the inner chine angle and having a marginal lap on the inner bottom plank panel so as to cross the joint between the inner side and bottom plank panels, and a water-tight flexible sheet interliner between the inner and outer bottom plank panels extending, on the one hand between the faces of the outer keel rabbet and the edge of the outer plank panel which fits in said rabbet, and on the other hand extending between the abutting faces of the joint between the outer side and bottom plank panels, folded about the lower edge of the outer side plank panel and having a marginal lap on the outer side panel.

5. Double planked boat hull construction com-

prising inner side and bottom plank panels and outer side and bottom plank panels, the respective inner and outer plank panels making abutting joints at the chine, a keel having stepped inner and outer rabbets, receiving respectively the 5 keel edges of the inner and outer bottom plank panels, said inner bottom plank panel being secured compressively against the upper face of the inner rabbet, with the water-excluding packing intervening, a water-tight flexible sheet interliner between the inner and outer side plank panels, folded about the chine angle and having a marginal lap on the inner bottom plank panel 10 so as to cross the joint between the inner side and bottom plank panels, and a water-tight flexible sheet interliner between the inner and outer bottom plank panels extending on the one hand 15 between the faces of the outer keel rabbet and the portions of the adjacent outer bottom plank panel setting in said rabbet, and on the other hand extending between the abutting faces of the joint between the outer side and bottom plank panels, folded about the lower edge of the outer side plank panel and lapping on the outer side 20 panel, said interliners being in adhesive 25 contact with the surfaces which they engage.

ANDREW J. HIGGINS.
